APPARATUS FOR WINDING TEXTILE YARNS

John K. Cochran, Hazleton, Pa., assignor to The Duplan Corporation, Hazleton, Pa., a corporation of Delaware

Application June 18, 1953, Serial No. 362,602

10 Claims. (Cl. 242—35.5)

The present invention relates to the winding of textile yarns and particularly to a mechanism utilizing a rotary yarn guide and producing various types of winds such for example as figure eights, spiral or straight, the change from one type to another being readily effected.

The invention is shown in connection with a machine which takes yarn from a supply package, sizes the yarn and winds it on a tube, although yarn may be wound in this manner and the sizing step omitted.

It is an object of the invention to provide a yarn winding machine in which various types of winds can be produced.

It is another object of the invention to produce these various types of winds by means of a rotary yarn guide the rate of rotation of which can be varied as respects the rate of rotation of the tube on which the yarn is wound.

It is a further object of the invention to provide such a rotary yarn guide which is both driven and supported by a belt thereby making it possible to eliminate any axle and thus possible to utilize such a guide.

It is a further object of the invention to provide means for stopping individual ones of the yarn guides of a machine at will.

Other objects and features of the invention will be apparent when the following description is considered in connection with the annexed drawings, in which:

Figure 1 is a vertical cross-sectional view of a yarn sizing and winding machine having incorporated therein the rotary yarn guides of my invention;

Figure 2 is a fragmentary side elevation of the machine of Figure 1;

Figure 3 is an enlarged side elevation of certain of the rotary yarn guides; and

Figure 4 is an enlarged cross-sectional view of one of the rotary yarn guides showing also the positioning of the driving and supporting belt therefor and of the guides for that belt. The section is taken on the plane of the line 4—4 of Figure 3.

Referring now to the drawings and particularly to Figure 1 there is shown at 10 a suitable frame for supporting the yarn winding apparatus. Vertically reciprocable upon the frame 10 are the rods 12 on which are mounted the traverse bars 13 which bars support the rotary guide mechanism in the manner to be described. Rods 12 are guided in bearings 14 and are caused to reciprocate under motor drive in any suitable manner such for example as the cam drive disclosed in my Patent No. 2,635,820, issued April 21, 1953.

Extending longitudinally of the machine are pipes or tubes 16 mounted upon the intermediate frame members 17 fixed to the frame 10. Mounted on the pipes 16 are the supporting members 18 on which spindles 20 are rotatably mounted, these spindles being driven by a belt 21, the belt being guided and held in place against the spindles by means of the idler rollers 22.

Mounted on the traverse bar 13 at spaced points therealong are brackets 23. Supported on the brackets 23,

2

as shown particularly in Figure 1, are longitudinally extending plates 24, these plates having circular openings therein, the vertical center line of these openings being slightly displaced from a side edge of a winding tube

5 26 mounted on an extension 25 of the spindle 20. As seen in Figure 2 the vertical center line of the circular opening is displaced slightly to the left of the left edge of each winding tube 26.

Extending forwardly from and fixed to each plate 24 adjacent the left hand edge of the circular opening mentioned, is a strip of fibre material 27 which cooperates with another like strip to form a brake. Mounted at either end of the plates 24 (one on either side of the machine) are pulleys, one of which is indicated at 28 in Figure 2. Adjustably mounted, as for example by means of the eccentric screws 29 shown in Figure 3 at spaced points adjacent the upper and lower edges of each plate 24, are ball bearing idler rollers 30, together with belt guides 31. A belt 32 passes over the pulleys 28 and bears against the idler rollers 30.

As will be observed by reference to Figures 1, 3 and 4, the idler rollers 30 are arranged in groups of four, two of which cooperate with the lower reach of the belt and two with substantially corresponding points on the upper reach of the belt. A rotary yarn guide 33, which is shown as a ring having a flanged rim is arranged at substantially the center of the rectangular figure formed by a group of idlers 30, the yarn guide 33 being supported upon the lower reach of the belt and held in place by reason of the belt passing between the flanges thereof. Further, since one pair of diagonally opposite rollers 30 (the pair at the upper right and lower left in Figures 2 and 3) is adjusted to be closer to the horizontal center line of ring 33 than the other pair, the rings are located laterally as well as vertically by belt 32.

As has already been stated, a vertically extending fibre piece 27 is mounted on the plate 24 adjacent the left hand side of each of the circular openings in the plate 24. This fibre piece extends between the upper and lower reach of the belt and forms a part of a brake mechanism.

Each rotary yarn guide is provided with a small eye fixed to the inner surface thereof as indicated at 34 and the yarn extends through this eye.

Lying on the opposite side of each yarn guide 33 from the fibre brake piece 27 already described is a similar fibre piece 35, this piece however being supported on an arm 36 oscillatably mounted on a stud fixed to the plate 24. Integral with the arm 36 is an operating lever 37 guided in a guide member 38 fixed to the plate 24 the lever being held in either of its adjusted positions by means of the screw 40 operating in a central slot in the member 41. Thus by raising lever 37 to its upper position the rotation of the associated yarn guide 33 may be stopped by gripping the guide 33 between the two fibre brake pieces 27 and 35.

When the brake levers 37 are in their lower position the yarn guides are free to rotate being driven by belt 32 which is in turn driven by the pulley 28. Pulley 28 has mounted on its shaft a second pulley 42. A V-belt 43 extends from a pulley 44 to the pulley 42. Pulley 44 is rotatably mounted on a shaft 45 supported on an arm 46 pivotally mounted on the frame 10. A link 47 extends from the end of arm 46 to the traverse bar 13, this link serving to maintain the relationship between pulleys 42 and 44 and thus keep the belt 43 taut irrespective of the vertical position of the traverse bar 13.

Mounted on the shaft 45 is a second pulley 48 driven by a pulley 50 mounted on shaft 51, shaft 51 also constituting the pivot point for arm 46. A V-belt 52 extends from pulley 50 to pulley 48. Shaft 51 is driven by means of a pulley 53 fixed thereon, a V-belt 54 extend-

ing from this pulley to a drive motor of the machine (not shown).

A yarn supply package is mounted in any suitable position on the machine frame as indicated, for example at 55. The yarn from this package passes through a guide 56, thence upwardly through a tensioning device 57, through a yarn cleaning member 58, and thence over the outer surface of a sizing roll 60, which roll is mounted on a shaft 61 driven in any suitable manner from the machine motor and operates in a trough 62 containing sizing material.

From the sizing roll the yarn passes over a yarn guide 64 fixed to arm 65 which is in turn fixed to the plate 24, thence through the eye 34 of the associated rotary yarn guide 33 and to the tube 26. As the tubes 26 rotate at high speed the rotary guides also rotate thus producing a conical path between each rotary guide and its associated tube or bobbin 26. As this occurs the traverse 13 moves slowly up and down. As a result and depending upon the speed ratio between the rotary guides 33 and the spindles 20, 25, various types of winds such as figure eights, spiral or straight can be effected and deposited layer upon layer until the tube is full. Moreover, the movement of the rotary guides 33 produces a taper at each end of the tube giving a crowned or barrel effect. The various types of wind which may be produced determine whether the package is to be hard or soft; package hardness may be further controlled by varying the tension applied in the tensioning device 57.

While I have described a preferred embodiment of my invention it will be understood that many other modifications may be made without deviating from the principles thereof; therefore I wish to be limited not by the foregoing description, but solely by the claims granted to me.

What is claimed is:

1. In a yarn winding machine of the type having a plurality of yarn-receiving tubes, said tubes being rotatably mounted, and having a traverse bar reciprocable with respect to the yarn-receiving tubes and parallel to the axes thereof, in combination, yarn guiding means mounted on the traverse bar for directing yarn to each of said tubes, said yarn-guiding means comprising a ring rotatably mounted adjacent the corresponding tube with its axis of rotation perpendicular to the tube and to the plane of reciprocation of the bar, the diameter of said ring being less than the axial length of the yarn receiving tubes, means for guiding the yarn through said ring at a point removed from its center and drive means for rotating said ring.

2. A device as claimed in claim 1, characterized in that said ring driving means also supports said ring.

3. A device as claimed in claim 2, characterized in that said ring rotating and supporting means comprises

a belt and said ring has a flanged rim, said belt operating within said flanges and being in contact with said rim at diametrically opposite points thereon.

4. A device as claimed in claim 3, characterized in that said yarn-receiving tubes are mounted on vertical axes and said belt extends horizontally having the upper and lower reaches thereof in contact with said ring for rotation of said ring by said belt.

5. A device as claimed in claim 4, characterized in that said belt is motor driven and said belt is common to all said rings, said belt extending along said machine adjacent said yarn-receiving tubes and supporting said yarn-guiding rings one adjacent each yarn-receiving tube.

6. A device as claimed in claim 4, characterized in that the linear speed of said belt is adjustable relative to the rotational speed of the yarn-receiving tubes and to the speed of reciprocatory movement of the traverse whereby the winding pattern may be varied.

7. A device as claimed in claim 4, characterized in that guiding means for said belt are provided in sets of four, said guiding means being arranged in rectangular form, said rectangle being circumscribed about said yarn-guiding ring.

8. A device as claimed in claim 7, characterized in that said belt-guiding means comprises rollers mounted on eccentric screws and further comprises guiding strips extending at either side of said belt.

9. A device as claimed in claim 7, characterized in that one diagonally opposite pair of said belt-guiding rollers is closer to the center of said yarn-guiding ring than is the other diagonally opposite pair whereby said rings are retained in proper position adjacent corresponding ones of said yarn-receiving tubes.

10. A device as claimed in claim 9, characterized in that a stationary fibre strip is positioned adjacent said ring on one side thereof and a second fibre strip is mounted at the opposite side of said ring on one arm of a bell crank lever, the other arm of which comprises an operating lever whereby said second fibre strip may be moved against said ring and individual ones of said yarn-guiding rings may be gripped between said fibre strips and thereby braked.
